UNITED STATES PATENT OFFICE

2,200,692

WINDOW

William Fairley, Oakland, Calif.

Application February 28, 1939, Serial No. 259,035

2 Claims. (Cl. 16—163)

This invention relates to improvements in windows, and has particular reference to a casement window wherein both sides of the window may be easily washed.

5 The principal object of this invention is to produce a device of this character which may be employed with the ordinary casement window.

A further object is to produce a device of this character which is simple in construction, and 10 therefore economical to manufacture.

15 A further object is to produce a device of this character which, to all intents and purposes, appears as an ordinary hinge.

Other objects and advantages will be apparent 20 during the course of the following description.

In the accompanying drawing forming a part 25 of this specification and in which like numerals are employed to designate like parts throughout the same,

20 Fig. 1 is a front elevation of a window equipped with my hinge;

Fig. 2 is a cross sectional view taken on the line 2—2 of Fig. 1;

25 Fig. 3 is an enlarged detail fragmentary view showing the window swung in for the purpose of washing the outside of the window;

Fig. 4 is a detail view of the hinge parts;

Fig. 5 is a detail perspective view of the latch; and

30 Fig. 6 is a fragmentary detail perspective view of the window sill and window frame.

The ordinary casement window merely swings outwardly from the window frame, with a result 35 that it is almost impossible to wash the outside of the window pane from the inside of a building.

40 Applicant has therefore devised a simple hinge arrangement whereby the window may be swung upon a second pintle when the same has been released from its ordinary swinging position, and can then be moved into the room for washing the outside thereof.

45 In the accompanying drawing wherein for the purpose of illustration is shown a preferred embodiment of my invention, the numeral 5 designates an ordinary window frame having a window sill 6 and drain board 7. To this drain board is attached a pivoted bottom stop 8. The sash is designated as a whole by the numeral 9. Secured to one side of the frame 5 are hinge plates 11 and 12. These plates 11 and 12 are respectively hinged to center plates 13 and 14 respectively, as by pintles 16 and 17 respectively. Extending between the plates 13 and 14 is an angle member 18, which serves to strengthen the hinge as

a whole. Pivoted to the plates 13 and 14 are sash engaging plates 19 and 21 respectively. A rod 22 extending parallel to the angle member 18 forms the pintle between the plates 13 and 19 and 14 and 21. A sliding catch 23 is mounted upon the rod 22 and has a bifurcated portion 24 which is adapted to engage a screw 26 for the purpose of preventing movement between the plates 13 and 19 and 14 and 21, except when it is desired to wash the outer side of the window. 10 This catch 23 extends on both sides of the angle member 18 so that when the screw-head 26 passes through a notch 20 formed in the angle member, the same will be rigidly held.

The manner of operating my device is as follows:—

Assuming that the parts are in the position shown in Fig. 1, which is the ordinary hinge condition of the window, and it is desired to swing the window so as to have the outer surface within 20 the room, the catch 23 is raised so as to disengage the bifurcated portion from the screw head 26, after which the window may be moved about the rod 22 and swung into the room as best illustrated in Fig. 3. When moving the window into the room, it is first necessary to move the stop 8 to the full line position of Fig. 2, which 25 permits the lower portion of the sash to pass through the window frame.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. In a device of the character described, a pair of hinge plates, a second pair of hinge plates hinged to said first mentioned plates, and a third pair of hinge plates adapted to be attached to a closure and hinged to said second mentioned hinge plates, a rod extending between and forming a pintle for the pivotal connection between said second mentioned hinge plates and said third mentioned hinge plates, and a sliding latch mounted on said rod adapted to co-operate with a screw carried by the closure.

2. In a device of the character described, a pair of hinge plates secured to a window frame, a second pair of hinge plates pivoted to said first mentioned hinge plates, an angle member extending between said second mentioned hinge plates, said angle member having a notch formed therein, a third pair of hinge plates adapted to be attached 55

to a closure and pivoted to said second mentioned hinge plates, a rod extending between said last mentioned hingedly engaged plates and forming a pintle for the pivotal connection between said second mentioned hinge plates and said third mentioned hinge plates, a catch slidably posi-

tioned on said rod, said catch straddling said angle member and being adapted to engage a screw carried by said closure when said closure is moved to project said screw through said notch.

WILLIAM FAIRLEY.
